FREDERIK VAN ROSEN HOOGENDIJK, OF BERKELEY, CALIFORNIA.

INTERNAL-COMBUSTION-ENGINE CONSTRUCTION.

1,400,746.

Specification of Letters Patent. Patented Dec. 20, 1921.

Application filed March 20, 1919. Serial No. 283,819.

To all whom it may concern:

Be it known that I, FREDERIK VAN ROSEN HOOGENDIJK, a subject of the Queen of Netherlands, residing at Berkeley, in the county of Alameda and State of California, have invented a new and useful Improvement in Internal-Combustion-Engine Construction, of which the following is a specification.

10 This invention relates to an internal combustion engine construction.

It is the principal object of this invention to provide an engine structure of the four cycle double acting type which is so designed as to produce a maximum amount of power within a minimum space and to further provide improved and novel arrangements of the operating mechanism in carrying out this idea.

20 The present invention contemplates the use of double-opposed cylinders, each set of cylinders having rigidly connected pistons directly driving the crank shaft, the operation of said cylinders being controlled by a 25 novel timing and reversing mechanism.

The invention is illustrated by way of example in the accompanying drawings, in which—

Figure 1 is a fragmentary view of one end 30 of the engine, showing parts in elevation and parts broken away to clearly disclose the mechanism.

Fig. 2 is a view in vertical section, as seen on the line 2—2 of Fig. 1, illustrating the 35 driving connections and the timing arrangement.

Referring more particularly to the drawings, 40 10 indicates a bed plate carrying the main bearings for the reception of a crank shaft 11. Superimposed upon the bed plate 10 are lower columns 12. The tops of the columns 12 are suitably formed to carry cylinder block 14, within which are mounted the lower engine cylinders 15. Disposed in 45 spaced relation to the cylinder block 14 is an upper cylinder block 16 carrying the upper engine cylinders 17. The two cylinder blocks 14 and 16 are held in rigid relation to each other by upper columns 18.

50 The main tie rods 19 run on either side of the main bearings from the bed plate 10 through the lower column 12, cylinder block 14, upper column 18 and cylinder block 16, thus connecting these various parts. The 55 cylinder construction is clearly shown in Fig. 2, where it will be seen that each cyl-

inder comprises an outer water jacket wall 20 and an inner cylinder wall 21, the outer jacket being securely fastened to the cylinder block 16 and formed integral with the 60 cylinder wall 21 as connected at 21', thus providing a rigid support for each cylinder and securing it to the main frame. The outer jackets extend to the cylinder blocks and are there united with a cylindrical wall 65 through which the cylinders 21 extend and by which a continuation of the jacket space is formed throughout the remaining length of each of the cylinders.

The opposed cylinders are exactly the 70 same and the axes of the sets of cylinders are in longitudinal alignment. This permits them to receive upper and lower pistons 22 which may reciprocate within the sets of cylinders and are secured together by two 75 rigid piston rods 23. These rods are spool-shaped and extend oppositely from a yoke 24 to which they are detachably secured. The outer ends of the rods are formed as 80 seats for the pistons 22. It will thus be evi-

dent from an examination of Fig. 1 that the yoke 24, the oppositely extending piston rods 23, and the pistons 22, are assembled to form a rigid unit which moves as a single 85 body and produces reciprocations of the two 90 pistons within the opposed cylinders. The yoke 24 extends oppositely from the longitudinal center of the piston structure and is formed with bosses through which parallel 95 yoke rods 25 extend. These yoke rods pass 100 downwardly along the opposite sides of the lower cylinders, through the cylinder blocks, and at their lower ends are secured within cross-head shoes 26. The cross-head shoes 26 are formed integral with a cross-head 27, within which the upper end of the connecting rod 13 is journaled. The cross-head 95 shoes 26 are also disposed between parallel and vertically extending ways 28 which are carried by the lower columns 12.

As shown in Fig. 1, the upper ends of the connecting rods 13 are formed with opposite trunnions 29 which are fitted with bushings 30. For convenience bushings 30 are detachably secured within the cross-head 27. 105 The cross-head 27 and its shoes 26 are permitted to slide along the ways, as produced by the action within the engine cylinders.

Reference being had to Fig. 2, it will be noted that each of the cylinders is formed 110 with a combustion chamber 31. This chamber extends at right angles to the longitu-

dinal axis of each cylinder. The chamber 31 communicates with extensions 32 which hold the housing for the intake and exhaust valves 33 and 34, both of which are of the 5 puppet type.

Mounted to communicate with the combustion chamber 31 is a suitable fuel valve and sprayer nozzle 35 which is preferably constructed as disclosed in my co-pending 10 application entitled "Fuel valve nozzle and sprayer construction," which application is filed concurrently herewith. Each of the extensions 32 is also fitted with an air valve 36 for starting purposes and a safety and 15 relieve valve 37. In the present instance, it is necessary for the valve structures to be disposed upon opposite sides of a horizontal center line of the engine and for that reason an intermediate cam shaft 38 is mounted in 20 bearings and extends horizontally of the structure.

This shaft 38 is shown in Fig. 2 as being fitted with sliding boxes 39, carried between guide brackets 40, which will permit the 25 shaft and boxes to move horizontally. Radius arms 41 and 42 are provided and are freely supported upon the cam shaft 38. These arms extend outwardly and in diverging directions and embrace cam shafts 30 43 and 43'. The cam shafts are parallel and are vertically superimposed. The intermediate cam shaft 38 is provided with a driving gear 44 in constant mesh with a driving gear 45 of the shaft 43 and the 35 gear 46 of the shaft 43', being held in this relation by means of the radius rods 41 and 42.

It is also to be noted that the shafts 43 and 43' are carried within sliding boxes 40 47' which may slide vertically along ways 46'. The boxes 47' are pivotally connected with eccentric arms 47 mounted upon a reversing shaft 48. It will thus be possible, 45 by rotation of the shaft 48, to simultaneously draw the shafts 43 and 43' toward each other or to force them away from each other as occasion demands. This movement is provided in order to permit the engine to be readily reversed and as the reversing 50 shaft is rotated in order to draw the cam shafts toward each other, cams 49 will be actuated to cause suitable movement of bell cranks 50. The bell cranks are pivotally mounted upon the side of the cylinder blocks 55 and at their free ends engage shifting collars 51. These collars are fixed upon the cam shafts and will produce a horizontal shifting 60 of the same.

The cam shafts carry a plurality of sets 65 of operating cams. These cams are in duplicate and are provided to operate a fuel rocker 52, an air starting rocker 53, the exhaust valve 34, and the air intake valve 33. In the present instance, the intake valve 65 is operated by means of a rocker 54 centrally

pivoted and carried upon an upright 55, the free end of this rocker, is fitted with a push rod 56, resting upon one of the operating cams 57. The air starting rocker 53 is provided with a push rod 58, the free 70 end of which rests upon one of cams 59. The fuel rocker 52 is provided with a push rod 60 resting upon one of the cams 61, while the exhaust valve 34 is actuated by a push rod 62 resting upon one of a pair 75 of cams 63.

A duplication of this structure is provided for each of the engine cylinders, and thus it is possible to operate the various 80 valve and fuel valve mechanisms in synchronism, either in a forward or reverse direction.

In operation, the engine is started by means of air, as is common, and the various 85 valves will thereafter operate in a manner which is evident and needs no further explanation. As the engine begins to function, the pistons 22 of each set will reciprocate and this reciprocal movement will be transmitted to the piston yoke 24, thereafter imparted to the vertical yoke rods 25; these rods at all times reciprocating vertically without pivotal movement between the ways 28. The pressure exerted by the lower ends 90 of the yoke rods will be transmitted to the cross-head 27 and will thereafter act through the connecting rods 13 to impart rotary motion to the crank shaft 11. In the event that the engine is to be reversed, the reversing shaft 48 is rotated by any suitable means. 100 This rotation will produce two simultaneous results, one being to draw the cam shafts 43 and 43' toward each other and the ends 105 of the rods 56, 58, 60 and 62 out of contact with the cams 47, 49, 61 and 63. As this motion takes place and the cams are free from the rollers, the expansion cam 49 will 110 swing the bell cranks in opposite directions and shift the two cam shafts longitudinally of the engine. The stroke of the shifting mechanism corresponds to the distance from center to center of the various cams upon the cam shafts 43 and 43'. It will be understood that the lift upon the complementary cams of the cam shaft is reversed 115 so that when the shaft has been shifted a reversal in sequence of the operation of the valve members will be produced and the engine thereby reversed in its direction of rotation. After the shafts have been shifted, 120 the reversing shaft may again be rotated to throw the cam shafts 43 and 43' outwardly and causing the cams to properly register with the ends of the push rods.

It will be noted that when any motion 125 is produced to move the shafts 43 and 43' toward or away from each other, this will act through the radius rods 41 and 42 to move the shaft 38 outwardly and thus compensate for the variation in the relative positions 130

of the three shafts 43, 43' and 48. This will maintain the gears 44, 45 and 46 in proper mesh at all times and will prevent them from binding. Motive power is furnished as desired from the crank shaft and in the present instance a gear ratio of 2 to 1 is established.

In case the pistons are to be removed, the cylinders remain unmolested. For the inspection of the lower piston or for the renewal of its piston rings the pistons are placed in top position and the lower piston is supported by two bars placed horizontally under the piston flange, whereupon the lower piston rod is taken out by removal of the bolts which connect same with the yoke and the lower piston. Then the yoke is lowered by turning the engine and the flange of the lower piston is bolted to the lower flange of the yoke. Thereafter the supporting bars may be removed and by again turning the engine the lower piston can be raised above its cylinder for inspection and renewal of piston rings.

By reversing the operation, the upper piston may be removed, thus making it possible to easily remove the pistons from the cylinders without molesting the cylinders or the valve mechanisms connected therewith.

It will thus be seen that the structure here disclosed embodies an improved design of a vertical, double-acting, four-cycle internal combustion engine, whereby the running of a piston rod through the lower combustion chamber and the exposure of the piston rod to the combustion temperature is avoided and whereby, through special arrangement, the pistons are easily removed without the usual objectionable dismantling of the cylinder structure.

Having thus described my invention, what I claim and desire to secure by Letters Patent is—

1. In an engine, a bed, lower columns on the bed, a lower cylinder block on the upper ends of the columns, a cylinder in the block, upper columns seated on the lower block, an upper cylinder block on the upper ends of the upper columns, a cylinder in said upper block, tie rods extending from the bed through all of the columns and the cylinder

blocks, pistons in the cylinders having rods a yoke connecting the rods and operating between the two blocks, yoke rods extending downwardly from the yoke ends and through the lower cylinder block, a cross-head connecting the lower ends of the yoke rods, vertical guides for the cross-head borne by the lower columns, and a crank shaft connected to the cross-head.

2. In an engine, a pair of spaced opposed cylinders, a piston in each cylinder, a yoke in the space between the cylinders, a piston rod for each piston of approximately spool shape, bolts connecting the enlarged inner ends of the spool-shaped rods to the yoke, and bolts connecting the enlarged outer ends of the spool-shaped rods to the outer ends of the pistons, whereby upon removal of the bolts the rods may be bodily moved laterally out of normal position and removed and the pistons then removed from their cylinders.

3. In an engine, a pair of spaced opposed cylinders, a piston in each cylinder, a yoke in the space between the cylinders, a piston rod for each piston having enlarged end parts to afford substantial seats engaged with the yoke and with the outer piston ends respectively, and means to removably secure the respective end parts of the rods to the yoke and to the pistons so that upon removal of said means the rods may be removed by a lateral bodily sliding movement thereof to allow of removal of the pistons.

4. In an engine, a pair of spaced opposed cylinders, a piston in each cylinder, a yoke in the space between the cylinders, a piston rod for each piston formed for interposition between the piston and the adjacent part of the yoke, and means to removably secure one end of each rod to its piston and the opposite end to the yoke so that upon removal of said means the rods may be removed by a lateral movement thereof to permit subsequent removal of the pistons.

In testimony whereof I have hereunto set my hand in the presence of two subscribing witnesses.

FREDERIK VAN ROSEN HOOGENDIJK.
